UNITED STATES PATENT OFFICE.

AUGUST J. KREUZKAMP, OF BROOKLYN, NEW YORK, ASSIGNOR TO ENGLANDER SPRING BED COMPANY, OF BROOKLYN, NEW YORK, A CORPORATION OF NEW YORK.

SPRING OR SPRING-MATTRESS.

1,100,379.

Specification of Letters Patent. Patented June 16, 1914.

Application filed September 26, 1913. Serial No. 791,916.

To all whom it may concern:

Be it known that I, AUGUST J. KREUZKAMP, a citizen of the United States, residing at Brooklyn, in the county of Kings and State of New York, have invented certain new and useful Improvements in Springs or Spring-Mattresses, of which the following is a specification.

This invention relates to improvements in springs or spring mattresses, the object of the invention being to provide an improved article of this class having an improved effective and efficient means which will not only prevent the slippage and spreading of a stuffed mattress on its spring and the consequent hanging and sagging over of the side edges thereof and which will maintain it in its original box-like form on the spring, but which will also provide a means for reinforcing and supporting the side edges of the spring or spring mattress in a very effective and durable manner. The object of the invention being to provide means which will accomplish all of the foregoing objects in a very simple and comparatively inexpensive manner by one and the same structure.

I am aware that side-guards of various forms have been patented and also aware that several patents have been obtained for reinforcing the side edges of the mattress, but with those devices for the latter purpose with which I am familiar, they are not efficient for also preventing the spreading and flattening of a stuffed mattress for the simple reason that they are so connected with the side edges of the spring at the center thereof that there is nothing to prevent at these points and for a considerable distance at each side thereof the spreading of the stuffed mattress when it becomes flattened in use, and consequently there is nothing to prevent at these points the side edges of the stuffed mattress sagging or hanging over the side edges of the spring and in consequence these devices will not maintain the stuffed mattress in its original box-like form, whereas by the present improvement not only is the stuffed mattress maintained in its proper place and in its proper shape, but the side edges of the spring are materially reinforced and supported at the points where they are ordinarily the weakest.

In the present improvement the structure

is such that at no point is there a sufficient opening to permit the stuffed mattress to project beyond the side edge of the spring, while at the same time the side edge of the spring is materially reinforced and supported at its weakest point and this by means of tangential or diagonal supports connected with the spring in such manner that the spring is supported at its side edges midway of its length, and which supports by reason of their tangential formation co-operate with horizontal members in such way as to fill the spaces between such horizontal members and so prevent the protrusion of the stuffed mattress and therefore its flattening and spreading. Moreover, the organization is such that the reinforcing tangentially located members permit the use in an effective and efficient manner of wire-formed coiled or spirally wound cables which would otherwise not be practicable, that is to say, when a cable formed of a series of interwoven wires, usually forming coils or spirals, is used, the cable has a certain elastic limit; in other words, the cable when made in this way, it usually being hollow, will stretch only a certain distance before its elastic limit is exceeded when it will not return to its normal condition and in consequence it becomes wobbly and is of no efficiency as a side-guard, and this is one reason why additional means is necessary in order to keep it taut. By the provision of this improved reinforcing means connected in the manner herein described with the bottom and with the horizontal spirally wound cables, these reinforcing members co-act with the cable and with the bottom in such manner that they prevent the elastic limit of the horizontal cable from being exceeded in that any stretching of the cable laterally or pulling thereon lengthwise is offset by the fact that this pull or stretching of the cable is also imparted to the diagonal reinforcing means and to the bottom, and this thus holds the small spirals or coils of the cable from being stretched beyond their elastic limit, and especially is this true by reason of the fact that the reinforcing tangentially located members have their ends connected adjacent to the ends of the guard. In short, the present improvement provides a side-guard which has much of the efficiency of a woven wire side-guard in that the connections between

the horizontal spirally formed cable and the bottom is such that the spirals of that cable cannot readily be pulled or stretched beyond their elastic limit.

- 5 In the drawing accompanying and forming part of this specification, Figures 1, 2, 3, 4, 5 and 6, illustrate side views of different forms of this improved side-guard and spring reinforcement.
- 10 Similar characters of reference indicate corresponding parts throughout the figures of the drawings.

In all the forms shown the spring 2 which may be of any suitable form, as of 15 woven wire or otherwise, is usually supported by suitable framework comprising cross-bars 3 carried by corner brackets 4 secured to side-bars 5. In the present instance, the spring or bottom is connected to 20 the cross-bars 3 by helical springs 6.

In all the forms of this improvement, it will be observed that the side-guard comprises in part one or more horizontally 25 stretched members 7 maintained under tension, these members being connected at their ends to brackets 8 upstanding from the cross-bars 3. In practice these horizontal members may be of single wire formation or of spiral cables as shown herein, and are 30 preferably connected with the upstanding brackets 8 by coil springs 9.

In Figs. 1, 2 and 5, but one horizontal member 7 is provided, while in Figs. 3, 4 and 6, a pair of such members is provided, 35 one below the other and spaced from each other.

It will also be noted in the various forms of the improvement that this side-guard comprises in part tangent reinforcing 40 means 10 so connected with the spring 2 or with the horizontal members 7 thereof that the center of the spring along its side edges is effectively reinforced.

In Figs. 1, 2, 3 and 4, a single reinforcing 45 medium is used, one at each side of the spring, while in Figs. 5 and 6, a pair of such reinforcing mediums is provided, the cables of each pair crossing each other intermediate the center and the ends of the 50 spring at each side of such center.

In all the forms of the present improvement it will also be observed that the reinforcing tangent supporting means is shown connected with the same helical springs with 55 which one of the horizontal members 7 is connected, although this may be otherwise in practice if desired.

In the form shown in Fig. 1, the reinforcing means 10 is connected with the spring 2 centrally thereof. The spring is usually provided with a reinforced edge 13 and the outer ends of the cable 10 are also connected with the helical springs 9, thus forming an effective means for reinforcing the side edges 60 of the spring.

In the form shown in Fig. 2, the reinforcing cable 10 is reversed, its outer ends being connected with the helical springs to which the ends of the spring 2 are connected, while it is connected centrally with the horizontal cable 7 and with the spring 2 by a suitable flexible connection 14. 70

In the form shown in Fig. 3, the reinforcement is connected with the spring 2 centrally thereof and with the coil springs 9 with which the upper cable 7 is connected, and also connected with the intermediate cable 7 as at 17. 75

In Fig. 4, the structure shown in Fig. 3 is reversed in that the reinforcing cable is connected centrally thereof with the upper horizontal cable 7, while its ends are connected to the same springs to which the bottom is connected. 80

In Figs. 5 and 6, a pair of reinforcing cables 10 are provided, one connected centrally thereof with the side of the spring 2, while its opposite ends are connected with the helical springs 9 with which the upper cable 7 is connected, while the other reinforcing cable 10 is connected centrally thereof with the cable 7, while its ends are connected with the helical springs 9 to which the spring bottom is connected. These reinforcing cables 10 are in turn connected together 85 where they cross each other as at 15.

The structure shown in Fig. 6 is similar to that shown in Fig. 5, except that it has an intermediate horizontal cable 7 to which the reinforcing cables 10 are connected at the 90 points where they cross each other. 100

In all the forms of the improvement it will be seen that the tangentially and horizontally located cables are so organized that the space between the horizontally located cables is materially taken up by the tangentially located cables so that each side-guard of the spring is a unitary one. There 105 is thus formed at each side of the spring a reinforced side-guard which not only prevents the flattening and spreading of the stuffed mattress, but which also reinforces the side edges of the spring at the points where it is the weakest and which reinforcement in turn serves not only the purpose of 110 reinforcing the spring but of also filling in the space between the horizontal cables in such manner that the protrusion of the stuffed mattress is prevented. This improvement thus accomplishes not only the 115 purposes stated, but also enables the horizontally located cables to be used in an efficient manner and to keep them properly spaced one from the other, since these reinforcing cables connected as described materially prevent the horizontal cables from being stretched beyond their elastic limit. 120

By forming the side-guard in the manner shown, not only are the side edges of the spring reinforced, but the side-guard is itself 125

reinforced by members which form a part of such side-guard and the several elements making up the guard are so connected that the whole guard will move as a unitary structure, while at the same time it will be flexible and maintained under tension so that it will normally return to its proper upright position when deflected therefrom. It will also be seen that the horizontal members of whatever form they may be, while connected with the spring bottom or with each other when several thereof are used, are nevertheless so connected with such bottom that weight on the bottom does not react merely on the cables intermediate the ends thereof but also on the upright supports or standards 8 secured to the rigid cross-bars 3. That is to say, by reason of the diagonally located cables 10, weight on the bottom is transmitted not merely to the cables 7 in a vertical direction, which would be the case if such cables were simply connected to the bottom by upright members, but is transmitted directly to the brackets 8 by reason of the fact that each reinforcement comprises one or more cables each connected with the bottom directly, either at the ends of the cable or intermediate such ends, so that strain on the bottom at the center thereof is transmitted to the brackets 8, thus relieving the cables 7 of a large part of the strain which would otherwise come thereon if such cables were merely connected with the bottom by members which were not in themselves connected with the brackets 8 through the medium of the helical springs 9.

I claim as my invention:

1. A spring comprising a bottom, having at each lengthwise extending side edge thereof a side-guard of substantially the same height from end to end for preventing the flattening and spreading of a stuffed mattress and comprising a horizontal member and a tangentially located reinforcing member connected with each other and with the bottom in such manner that one reinforces the other, said reinforcing member having its opposite ends secured adjacent to the ends of the guard.

2. A spring comprising a bottom, having at each lengthwise extending side edge thereof a side-guard of substantially the same height from end to end for preventing the flattening and spreading of a stuffed mattress and comprising a horizontal member and a tangentially located reinforcing member connected with each other and with the bottom in such manner that one reinforces the other, and a helical spring connecting the ends of such horizontal member and tangentially located reinforcing member, with suitable supporting means.

3. A spring comprising a bottom, having at each lengthwise extending side edge thereof a side-guard of substantially the

same height from end to end for preventing the flattening and spreading of a stuffed mattress, and comprising a plurality of horizontal members and a tangentially located reinforcing member connected with each other and with the bottom in such manner that one reinforces the other, said reinforcing member having its opposite ends secured adjacent to the ends of the guard.

4. A spring comprising a bottom, having at each lengthwise extending side edge thereof a side-guard of substantially the same height from end to end for preventing the flattening and spreading of a stuffed mattress, and comprising a plurality of horizontal members and a tangentially located reinforcing member connected with each other and with the bottom in such manner that one reinforces the other and helical springs connecting said tangentially and horizontally located members with suitable supporting means.

5. A spring having at each lengthwise extending side edge thereof a side-guard of substantially the same height from end to end for preventing the flattening and spreading of a stuffed mattress, and including a connected tangentially located member, said tangentially located member having its opposite ends secured adjacent to the ends of the guard.

6. A spring comprising a flexible bottom member having at each lengthwise extending side edge thereof a side-guard member of substantially the same height from end to end for preventing the flattening and spreading of a stuffed mattress and a tangentially located member spaced from one of said members its greatest distance midway of the length of the bottom member.

7. A spring having at each lengthwise extending side edge thereof a side-guard of substantially the same height from end to end for preventing the flattening and spreading of a stuffed mattress, and comprising a plurality of connected tangentially located members spaced midway of their length.

8. A spring having at each lengthwise extending side edge thereof a side-guard of substantially the same height from end to end for preventing the flattening and spreading of a stuffed mattress, and comprising a plurality of tangentially located members spaced midway of their length connected with the bottom, and a horizontal member connected therewith.

9. A spring having at each lengthwise extending side edge thereof a side-guard of substantially the same height from end to end for preventing the flattening and spreading of a stuffed mattress and comprising a plurality of tangentially located members spaced midway of their length connected with the bottom and a plurality of

horizontal members spaced from one another and connected with said tangentially located members.

10. A spring having at each lengthwise 5 extending side edge thereof a side-guard of substantially the same height from end to end for preventing the flattening and spreading of a stuffed mattress and comprising one or more horizontal members 10 and tangentially located means crossing the spaces between and connected with said members and having its opposite ends connected adjacent to the ends of the guard.

11. A spring having at each lengthwise 15 extending side edge thereof a side-guard of substantially the same height from end to end for preventing the flattening and spreading of a stuffed mattress and comprising one or more horizontal members and tan- 20 gentially located means extending from end to end of the spring and crossing the spaces between said horizontal members.

12. A spring comprising a bottom, having at each lengthwise extending side edge 25 thereof a side-guard of substantially the same height from end to end for preventing the flattening and spreading of a stuffed mattress and comprising a horizontal coiled member and a tangentially located rein- 30 forcing member connected with each other and with the spring bottom and having its opposite ends secured adjacent to the ends of the guards.

13. A spring comprising a bottom having 35 at each lengthwise extending side edge thereof a side-guard of substantially the same height from end to end for preventing the flattening and spreading of a stuffed mattress and comprising a horizontal mem- 40 ber and a tangentially located reinforcing member connected with said horizontal member and also with the spring at the ends thereof.

14. A spring comprising a bottom having 45 at each lengthwise extending side edge thereof a side-guard of substantially the same height from end to end for preventing the flattening and spreading of a stuffed mattress and comprising a horizontal mem- 50 ber and a tangentially located reinforcing member, said reinforcing member connected with the bottom intermediate its ends and also supported at its ends adjacent to the ends of the bottom and having connection 55 with said horizontal member.

15. A spring having at each lengthwise extending side edge thereof a side-guard of substantially the same height from end to end for preventing the flattening and 60 spreading of a stuffed mattress and comprising one or more horizontal members and

a plurality of tangentially located reinforcing members crossing each other a plurality of times intermediate their ends and having connection with each of said horizontal members intermediate their ends and with the bottom. 65

16. A spring having at each lengthwise extending side edge thereof a side-guard of substantially the same height from end to 70 end for preventing the flattening and spreading of a stuffed mattress and comprising one or more horizontal members and a plurality of tangentially located reinforcing members crossing each other a plurality 75 of times intermediate their ends and having connection with each of said horizontal members intermediate their ends and with the bottom, and coil springs connected with the ends of said horizontal and reinforcing members.

17. A spring comprising a bottom having at each lengthwise extending side-edge thereof a side-guard of substantially the same height from end to end for preventing 85 the flattening and spreading of a stuffed mattress and comprising one or more horizontal members and a tangentially located reinforcing member, and an upright member carried by the bottom and connected with a 90 member or members of said guard for maintaining the same spaced from the bottom.

18. A spring comprising a bottom having at each lengthwise extending side-edge thereof a side-guard of substantially the 95 same height from end to end for preventing the flattening and spreading of a stuffed mattress and comprising one or more horizontal members and a tangentially located reinforcing member, and an upright mem- 100 ber carried by the bottom and connected with a member or members of said guard for maintaining the same spaced from the bottom, said member being located midway of the length of the bottom. 105

19. A spring comprising a bottom having at each lengthwise extending side-edge thereof a side-guard of substantially the same height from end to end for preventing the flattening and spreading of a stuffed mattress and comprising a horizontal member consisting of interwoven spirally formed wires and a tangentially located reinforcing member having its opposite ends secured adjacent to the ends of the guard, and an upright member connected with the bottom and effective to connect one of said members therewith and maintain it spaced therefrom. 110 115
